UNITED STATES PATENT OFFICE.

WILLIAM D. GRAVES, JR., OF PRESQUE ISLE, MAINE.

KNIFE-GRINDING MACHINE.

SPECIFICATION forming part of Letters Patent No. 425,781, dated April 15, 1890.

Application filed February 1, 1890. Serial No. 338,919. (No model.)

To all whom it may concern:

Be it known that I, WILLIAM D. GRAVES, Jr., of Presque Isle, in the county of Aroostook and State of Maine, have invented a new and useful Improvement in Knife-Grinding Machines, of which the following is a full, clear, and exact description.

My invention relates to improvements in knife-grinding machines, and has for its object to provide a simple, compact, automatically-acting device, whereby straight-edged knives for various machines may be ground to a bevel edge rapidly and accurately.

To this end my invention consists in the construction and combination of parts, as is hereinafter described and claimed.

The essential features embodied in the invention consist of a supporting-frame, whereon a longitudinally-sliding knife-carrying table is mounted, which receives reciprocatory motion from gearing that automatically reverses the longitudinal movement of the table, as will be more specifically described.

Reference is to be had to the accompanying drawings, forming a part of this specification, in which similar letters of reference indicate corresponding parts in all the figures.

Figure 1 is a front elevation of the machine. Fig. 2 is an end elevation of the same, the knife-supporting table being broken away, and a portion of a grindstone shown with the knife bearing thereon; and Fig. 3 is a transverse sectional elevation of the same, taken on the line 3 3 in Fig. 1.

35 A represents the frame of the machine, and consists of two housing-pieces *a*, vertically erected on the base-plate *a'*, a proper space intervening said housings for the reception of other parts.

40 On the upper portion of the housings *a* axially-coincident boxes *a*² are formed, in which a cylindrical shaft *b* is supported to rock and slide, and below the shaft *b* grooves are formed in the boxes *a*² for loosely supporting a rack *b'*, which is held in place longitudinally by the hub ends of the knife-supporting frame hereinafter described.

45 A skeleton knife-supporting frame *B*, consisting of the platen *c* and arms *c'*, is secured upon the shaft *b* by mounting the enlarged hub ends *c*² of the arms *c'* on the terminals of

the shaft, set-screws being provided, which afford means for attaching the frame *B* to the shaft.

The boxes *d*, that are formed in the upright housings *a* at a suitable distance above the base-plate *a'*, have their true horizontal bores in alignment for the revoluble support of the driving-shaft *C*, that projects outside of the frame at one side and has a pulley *e* secured on said projecting portion. Upon the shaft *C* two transverse rock-arms *f* of equal dimensions are mounted, said arms being transversely perforated of a diametrical size to fit and rock upon the shaft near their longitudinal centers, which will afford laterally-projecting portions of equal length for each arm *f*. At equal distances from the center holes in the rock-arms *f* said arms are perforated for reception of the ends of the short journal-shafts *g*, that are each secured to the rock-arms, thereby affording a stable rocking frame, and on these journal-shafts *g* worm-sleeves *g*² and pinions *g*³, integral therewith or secured thereto, are loosely mounted.

Upon the driving-shaft *C* a pinion *g*³ is secured, so as to align with the pinions *g*³, which pinion is of such proportionate diameter that it will mesh on opposite sides with each of said pinions *g*² and revolve them in different directions.

Between the pinion *g*³ and the rock-arm *f* which is farthest removed therefrom a spiral spring *h* is placed on the shaft *C* and compressed, so that the expansion of the spring 85 longitudinally upon the shaft will force the rock-arm it presses upon in frictional contact with the adjacent true face of the collar *i*, which is secured to the shaft *C*, and consequently revolves with it.

The worm-threads on the sleeves *g* are pitched in opposite directions, and the distance from the axis of the shaft *C* to the outer peripheral edge of each worm is such with regard to the position of the teeth on the rack-bar *b'* that said worms may be successively caused to engage the rack-teeth by a half-revolution of the rock-arms *f* on their support.

In the upper part of each flange-piece or lateral brace *a*³, formed on the upright housings *a*, open guide-slots are produced, which

are downwardly and inwardly inclined and receive the composite tappet-bar m and loosely support it to move endwise. The tappet-bar m consists of a straight rectangular metallic bar having a length proportioned to the capacity of the machine, and on its side two similar shifting-dogs m' are secured, their adjacent ends, which are imposed upon the side of the bar, being removably attached thereto by screws or other means. The free end portions of the shifting-dogs m' are given equal return-bends toward each other, which locates their locking-toes m^3 in the same horizontal plane in such relative position that the lugs n , which project from the outer faces of the rock-arms f at opposite ends thereof, will either of them engage an opposing toe m^3 when the parts are moved to cause such alternate abutment of the toes and lugs, as will be further explained.

Movable abutment-collars $o o'$ are mounted on the body of the sliding rack-bar b' outside of the supporting-boxes a^2 , and are also designed to limit the longitudinal movement of the rack-bar b' by their impingement on the tappet-bar m .

In operation the knife-blank D , which is to be bevel-ground on the stone or emery-wheel D' , is clamped or temporarily bolted upon the platen c , which will thus sustain the blank with its edge projected to engage the face of the grinding-wheel D' . Below the platen c a vertical post E is erected, which is adjustable for height, so that its upper end e' will engage the platen and arrest the grinding action in an obvious manner. Rotation of the driving-shaft C will cause the rock-arms f of the bracket-frame, which has contact with the collar i , to move around on the shaft C until a worm-sleeve g is aligned with the rack-bar b' and the worm-thread thereon meshes with the rack-teeth, as shown in Fig. 1, the proper alignment of the rack and worm being determined by the abutment of the moving lug n with the locking-toe m^3 of the tappet-bar m . The rotation of the worm-sleeve g by the pinions $g' g^2$ will longitudinally move the rack-bar b' until the collar o thereon, which is approaching the end of the tappet-bar m , abuts against it, shifting said bar sufficiently to release the interlocking connection of the lug n with the toe m^3 . The rock-arms f will now be moved together and cause the other worm-sleeve to mesh its worm-thread with the rack-bar b' . The longitudinal movement of the rack-bar b' carries with it the knife-supporting platen c , causing the edge of the knife-blank D to be progressively engaged with the stone or emery-wheel D' , and when the opposite abutment-collar o' is brought into contact with the tappet-bar the motion is again reversed. It is to be understood that the collars $o o'$ are so adjusted to the length of the knife to be ground that the latter will be made to traverse the stone or emery-wheel D' from one end to the other of the knife and grind it to a true bevel edge. Furthermore,

the interlocking of the toe on one end of the tappet-bar with an opposing lug is maintained until the knife-blank has been made to engage the stone throughout its length, when the reversed movement of the blank is effected in the manner hereinbefore explained.

By adjustment of the abutment-collars $o o'$ toward the boxes a^2 of the frame the reciprocal travel of the knife-carrying frame B may be shortened to suit knives which do not require the full longitudinal movement of the device to sharpen the edges of the same.

Slight changes might be made in the construction and arrangement of the working parts of this device within the manifest scope of my invention; hence I do not desire to limit the same to the precise forms herein shown.

Having thus described my invention, what I claim as new, and desire to secure by Letters Patent, is—

1. In a knife-grinding machine, the combination, with a knife-carrying table supported to slide with a longitudinally - reciprocable rack-bar, of oppositely-threaded worm-sleeves adapted to successively engage the rack-bar and reciprocate it and means for rocking the worm-sleeves toward the rack-bar alternately and revolving them oppositely, substantially as set forth.

2. In a knife-grinding machine, the combination, with an upright frame and a knife-carrying frame engaged by a longitudinally-reciprocable rack - bar, of revoluble worm-sleeves having oppositely-pitched threads and supported to rock on a driving-shaft, so as to alternately engage the rack-bar teeth, a driving-shaft, and means for revolving it, substantially as set forth.

3. In a knife-grinding machine, the combination, with a frame, a sliding rack-bar thereon, a knife-carrying frame on a rocking shaft, and a longitudinally-movable tappet-bar on said frame, of a driving-shaft revolubly supported on said frame, revoluble worm-sleeves threaded oppositely and supported to rock on the driving-shaft alternately to engage the rack-bar, gearing for rotating the worm-sleeves in opposite directions, means for rotating the driving-shaft, and a device, substantially as shown, for successively retaining the worm-sleeves in gear with the rack-bar, substantially as set forth.

4. In a knife-grinding machine, the combination, with an upright frame, a sliding rack-bar on said frame, a knife-carrying frame adjustably secured on a rocking and sliding shaft, and a tappet-bar mounted on said frame, of oppositely-threaded worm-sleeves and a driving-shaft on which said worm-sleeves are mounted to rock, said worm-sleeves being adapted to be alternately thrown into engagement with the rack-bar by the conjunctive sliding movement of the rack-bar and rocking movement of the worm-sleeves, substantially as set forth.

5. In a knife-grinding machine, the combination, with an upright frame having spaced housings and a base, a rack-bar supported to reciprocate in said frame, a knife-carrying frame adjustably secured on a shaft journaled on the frame, and a tappet-bar mounted to slide on said frame, of a driving-shaft revolvably supported on the housings of the upright frame and carrying a pulley, rock-arms loosely mounted on the driving-shaft, oppositely-pitched worm-sleeves revolvably supported by
- 10 said arms, a pinion secured on each of said worm-sleeves, an intermediate pinion mounted on the driving-shaft and meshing with the pinions on the worm-sleeves, and a spiral spring on the driving-shaft bearing on the intermediate pinion and one rock-arm thereon, substantially as set forth. 15
